CONTROL SYSTEM FOR IGNITER TORCH
 Jack A. Schuss, Hartford, Conn., assignor to Combustion
 Engineering, Inc., Windsor, Conn., a corporation of
 Delaware

Filed Aug. 25, 1961, Ser. No. 133,838
 4 Claims. (Cl. 158—28)

This invention relates to igniter apparatus in the form of auxiliary burners used as pilots or igniter torches for lighting other fuel streams delivered into a furnace as by means of tilting burners, or any other main burners, and it has particular reference to the control and indicating means associated with such igniter torches.

Where fuel, such as pulverized coal, is delivered into large furnaces, it is usual to have pilots or auxiliary burners using oil or gas to ignite said fuel. In addition warm up guns are generally needed in firing the first set of burners. As the furnaces get larger and larger, and thereby contain more burners, the problem of igniting these burners or pilots in a safe, efficient, and economical manner becomes greater. There is an increasing tendency now towards remote operation of the burners from a main control board. In doing so, some indicating means must be provided at the control board to inform the operator in the event that the igniters are not operating properly, so that necessary repairs and adjustments may be made. Furthermore, some means must be provided for terminating the flow of fuel to the igniter torches or pilots when a flame is not established, and also to prevent fuel from being supplied to the main burners when the pilots are not lit, to prevent the accumulation of a large combustible mixture within the furnace, which could lead to costly and dangerous explosions.

It is an object of this invention to provide a control for the igniter torches of a furnace, whereby the fuel to such torches is automatically terminated in the event that no flame is established.

It is another object of this invention to provide a reliable indication at a remotely located control board as to whether or not a flame has been established at the igniter torches.

It is a further object to test, or check out the flame sensing means prior to allowing fuel to flow to said pilot, to make sure it is in proper working order, and will not give out an inaccurate signal.

It is a further object to provide means whereby fuel cannot be supplied to the main burner unless or until a flame exists at its corresponding pilot.

It is a still further object to accomplish the above by means of an economical, simple, and compact control arrangement, with a minimum number of control components required.

Other objects and advantages will become apparent from the following description of the illustrative embodiment of this invention when considered with the accompanying drawing, wherein:

FIGURE 1 is a combined schematic and diagrammatic representation of the improved control apparatus of the present invention;

FIGURE 2 is a contact diagram for the master control switch which my new control system utilizes.

Looking now to FIGURE 1, 10 depicts a pilot or igniter torch unit, containing a torch nozzle 12 to which oil and atomizing air are supplied, and an ignition means such as a spark plug 14, by means of which the fuel and air mixture is ignited. Combustion air is supplied by means of pipe 13. An igniter torch unit such as the one shown is provided for each main burner existing in the furnace, and is positioned adjacent each main burner, so that the flame therefrom can ignite and/or stabilize

2

the combustible mixture issuing from the main burner nozzle.

The present control system is arranged so that all of the igniter torches or burners can be started up by an operator from a central or distant location. The control system comprises a master control switch 20, which can be mounted on a control panel located remotely from the furnace. The control switch 20 has four positions in which it may be placed, these being "off," "trip," "operate" and "ignite."

The control switch 20 consists of a number of cam actuators which will close various ones of the switch contacts A₁, A₂, A₃, A₄, B, C, D, and E, depending in which position the switch 20 is placed. The control illustrated is that which would be used to control the firing of four igniter torches, such as a set which would be used to light and/or stabilize tilting tangential main burners, one of which would be mounted in each of the four corners of the furnace.

20 The broken lines 30 and 40 indicate the control cabinets located adjacent to two of the pilot torches, two more not being shown. The components of all four of the control cabinets are actuated by master control switch 20. A suitable source of electrical energy 50 is provided.

25 The four control cabinets, each adjacent to one igniter torch, are identical with one another, and contain the same components. The components of control cabinet 30 will now be described, it being understood that each of the other three are identically constructed.

30 The control cabinet 30 houses a mechanical latch relay mechanism 60. The mechanical latch relay mechanism 60 consists of coils 62 and 116, one normally closed switch 72, and four normally open switches 76, 78, 80, and 82. Switches 72, 76, 78, 80, and 82 are mounted on a rod 83,

35 which is biased to the left by tension spring 104 when neither of the coils 62 or 116 is energized. The rod 83 is pivotally connected to arm 118, to permit longitudinal movement thereof. Arm 83 contains a hook 108 on its right end which coacts and engages with the hook on member 106 to hold it in its rightward position when coil 62 is energized. Arm 106 is pivotally connected to fixed member 112, and tension spring 114 urges the arm downwardly so that it normally is supported on rest 110. When coil 116 is energized and lifts hook arm 106 upwardly, 45 spring 104 pulls rod 83 to the left again.

Also contained within control cabinet 30 is a transformer 66 for energizing the spark plug or ignition means 14, and solenoids 84 and 88 which actuate oil valve 86 and air valve 90, respectively, which controls the supply 50 of oil and atomizing air to the igniter torch 10. Switch 92 is actuated by flame sensing means 95 to close either right hand contact 100, or left hand contact 102. Flame sensing means 95 consists of a diaphragm 94 which is exposed on opposite sides to the static pressure which exists at two fixed points within torch 10 by means of air lines 96 and 98. When no flame exists in the igniter torch, there is little or no pressure differential existing between lines 96 and 98, and switch 92 is biased to the right to close contact 100. When a flame is present, the static pressure in line 98 increases, thus moving switch 92 to the left to close contact 102.

55 Indicating light L₁, which is mounted on the control panel along with control switch 20, gives a visual indication to the operator whether or not a flame exists at igniter torch 10. Lights L₂, L₃, and L₄ perform the same function for the other three torches controlled by switch 20.

60 The operation of the control system will now be described. When it is desired to start up the furnace, and ignite the pilot torches, the operator moves control switch 20 from the "off" position to the "ignite" position. This closes contacts C and E by means of their associated cam

actuated switches. Closing contacts E completes the circuit to energize transformer 66 through conductors 64 and 68, to produce the necessary spark at spark plug or ignition means 14. If at this time the flame sensing means 95 is in proper working order, indicating a no flame condition of pilot 10, switch 92 will be biased to the right by compression spring 91, closing contact 100. If this condition exists, then operating coil 62 will be energized through contacts E, normally closed switch 72, contact 100, and conductor 68.

Energization of operating coil 62 pulls arm 118 and also rod 83 to the right, thereby opening the normally closed switch 72 and closing the four normally open switches. Although this deenergizes coil 62 by opening switch 72, rod 83 is held in its right position by engagement of hook 103 with the hook on arm 106. Closing of contacts C immediately energizes solenoid 88, thereby opening air valve 90 allowing atomizing air to flow to the igniter torch. The air from 13 to support combustion is controlled by other means. Movement of rod 83 to the right also closes normally open switch 78, energizing solenoid 84, thereby opening oil valve 86 to allow fuel to flow to the igniter torch 10. With air and fuel thus flowing to the torch, and with the ignition means 14 thus being energized by means of transformer 66, combustion should take place in the pilot burner 10. Establishment of a flame creates a pressure differential in lines 96 and 98 to move switch 92 to the left, closing contact 102. Since switch 80 is now closed, L₁ on the control panel will light up, current flowing through contacts C and conductor 121 to L₁, the circuit being completed through conductor 122, switch 80, contact 102 and conductor 68. This indicates to the operator that combustion has taken place at igniter torch 10, and that a flame exists there. All of the above operations take place automatically within a few seconds if everything works properly, when master control switch 20 is moved to its "ignite" position.

After a predetermined short time, possibly 2 seconds, switch 20 is automatically moved to its "operate" position when the operator releases it. This can be accomplished by a tension spring 22 which will return switch 20 to the "operate" position when the handle is released. In this position, contacts E are opened, and contacts B and D are closed, with contacts C also remaining closed. Opening of contacts E deenergizes the ignition transformer 66, thus extending the useful life of spark plug 14 by using it as little as necessary. Closing of contacts B completes a circuit through switch 76 and conductor 128 to a switch corresponding to switch 76 in each of the other three control cabinets for the other three igniter torches. If a flame has been properly established in each of these igniter torches, then relay 129 is energized, thus closing a pair of switches which complete an interlock system. These switches could when closed, for example, permit the start of the coal mill and coal feeders 150, which supply pulverized coal to all four of the associated main burners. Since the circuit contains each switch corresponding to switch 76 of each control cabinet in series, plus contact B of the control switch which closes in the "operate" position, it is obvious that if one of the igniter torches failed to establish a flame by the time the control switch is released to its "operate" position, associated relay contact 76 or one corresponding to it would reopen (if previously closed on satisfactory differential pressure checkout) and hence relay 129 will fail to stay energized.

With contacts D closed when control switch 20 is in the "operate" position, if the flame should go out or fail to be established at burner 10, then a circuit is completed to reset coil 116 through contacts D, switch 82, contact 100, and conductor 68. Energization of coil 116 lifts arm 106 upwardly disengaging the hooks, and thus allowing spring 104 to move rod 83 and the associated switches to the left, to their normal or original positions. If this happens, the light L₁ goes out, and the solenoid 84 of the oil valve is deenergized, by opening of switches 89 and 78,

respectively. Then in order to start up again, it would be necessary for the operator to again place control switch 20 in its "ignite" position, and if it failed again, he should check to see where the trouble is.

When orderly shut down of the ignition system is desired, the control switch 20 is placed in the "trip" position thereby closing contacts A₁, A₂, A₃ and A₄, opening contacts B, with contacts C and D remaining closed. A circuit through the reset coil 116 which bypasses the differential pressure switch 92 by way of switch 82, conductor 124 and contacts A₁, is established. The result is closure of the oil valve 86 and the de-energization of the indicating light L₁, indicating that the fire at burner 10 is out. Switch 82 opens upon movement of rod 83 to the left, thereby deenergizing reset coil 116, and switch 72 closes, resetting the circuitry to operating coil 62 for the next operating cycle. With no power required to feed any of the ignitor control components, the master control switch 20 can now be placed in the "off" position.

Numerals 130, 132, and 134 indicate conductors which extend to the other three control cabinets from contacts E, D, and C, respectively, so that these controls operate in the same manner as the one described. Contacts A₂, A₃, and A₄ perform in the same way as does A₁, and lights L₂, L₃, and L₄ indicate the flame condition for their corresponding burners or pilot torches.

While a control system has been described where the torches are associated with coal fired main burners and the igniter light off of all four igniters is a prerequisite for the start up of an associated coal mill, this control system can equally as well be adapted to an arrangement whereby each individual ignitor is interlocked with an associated oil or gas fired main burner. Also, any number of igniters can be controlled by a single master control switch 20. If gas, rather than oil is used as a fuel for igniter torch 10, then the atomizing air is not necessary, and air valve 90 and its associated solenoid 88 could be omitted from the control cabinets.

The integral operation of a group of four igniters is shown controlled by manipulation of a manually actuated switch 20; however, the arrangement can also be adapted to operation by a digital or analog computer supervised control system where switch 20 is superseded by electromagnetic relays or static switching devices, the switch 20 then being retained to provide an alternate mode of operation when control is switched to "hand" operation. If this were done, the signal energizing the indicating light L₁ could also be used to provide a feedback pulse, to automatically clear the computer for the next step in the operational sequence. Whatever, the mode of operation, whether manual or automatic, the same internal igniter cabinet control arrangement as illustrated would be used.

The advantages of my control system should now be apparent. The system provides an automatic check out or test of the flame sensing means to make sure it is in proper working order before an attempt is made to ignite the pilot or igniter torch. For example, if switch 92 is stuck in its position closing contact 102, or the differential pressure diaphragm is faulty so as to hold the switch 92 in a position other than in its right hand position closing contact 100, then when control switch 20 is moved to its "ignite" position, operating coil 62 will not be energized, and the subsequent sequential operations will not take place. If such condition arises, the fuel valve 86 will not be opened, nor will L₁ light up, and the operator will thereby be notified that the flame sensing means is not functioning properly. In this manner when L₁ lights up, it informs the operator of two things: (1) that the differential pressure switch and the flame sensing means is in satisfactory operating condition; and (2) that a flame has been established.

Other advantages are that under no conditions will fuel be supplied to the igniter torch for more than a few seconds without the presence of a flame; the ignition transformer is energized only for a short period of time when

the control switch is in the "ignite" position, which contributes to the long life of the spark plug; and the energization of the coils of the mechanical latch relay mechanism is of momentary duration only, thus preventing any great heat addition to the control cabinets from this source.

While I have illustrated and described a preferred embodiment of my novel control organization it is to be understood that such is merely illustrative and not restrictive and that variations and modifications may be made therein without departing from the spirit and scope of the invention. I therefore do not wish to be limited to the precise details set forth but desire to avail myself of such changes as fall within the purview of my invention.

What I claim is:

1. An igniter torch and main burner control system comprising in combination, a main burner, means to control the flow of fuel to said main burner, an igniter torch for said main burner, means to control the flow of fuel to said igniter torch, ignition means for the fuel of said igniter torch, flame sensing means for detecting whether or not a flame is issuing from said igniter torch, means for testing the flame sensing means to determine whether or not it is in working order prior to allowing fuel to flow to either the main burner or the igniter torch, means for positioning said fuel controlling means of the igniter torch such that fuel is supplied to said igniter torch only if the flame sensing means is in working order, said flame sensing means being capable of stopping the flow of fuel to said igniter torch in the event no flame exists after said ignition means have been energized and fuel is flowing to the burner, said main burner fuel flow control means allowing fuel to flow to said main burner only if and after a flame exists at said igniter torch.

2. The igniter torch and main burner control system of claim 1, including an indicating means responsive to said flame sensing means which indicates whether or not a flame is present at said igniter torch.

3. The igniter torch and main burner control system of claim 1, whereby said flame sensing means includes a pressure differential actuated means which is responsive to the static pressure existing at two spaced points within said igniter torch.

4. In a burner control system, a burner, means to control the flow of fuel to said burner, ignition means for the fuel, flame sensing means for detecting whether or

not a flame is issuing from said burner; an electrical system comprising a first circuit having a transformer capable of energizing said ignition means and a first switch means E in series therein; a second circuit having said first switch means E, a second switch means 72, a first relay 62, and a third switch means 92, 100 in series therein; a third circuit having a fourth switch means C, a fifth switch means 78, and a solenoid capable of actuating said fuel control means in series therein; a fourth circuit having a sixth switch means D, a second relay 116, a seventh switch means 82, and said third switch means 92, 100 in series therein; a member to which said second 72, fifth 78 and seventh 82 switch means are attached; means biasing said member to a first position in which said second switch means 72 is closed and said fifth 78 and seventh 82 switch means are open; latch means for holding said member in a second position in which said fifth 78 and seventh 82 switch means are closed and said second switch means 72 is open; said second relay 116 when energized being capable of releasing said latching means so that the member will be biased to said first position; said first relay 62 when energized being capable of moving said member to its second position; said third switch means 92, 100 being closed when no flame is present in the burner; said flame sensing means being capable of opening said third switch means 92, 100 when a flame is present in the burner; and a control switch means 20 which in a first position closes said first E and fourth C switch means, leaving said sixth switch means D open, and which in a second position closes said fourth C and sixth D switch means, leaving said first switch means E open; whereby said burner can be ignited and put into operation by movement of said control switch means 20 to its first position, followed by consequent movement to its second position.
